UNITED STATES PATENT OFFICE.

JOHN W. AMES, OF EAST RUTHERFORD, NEW JERSEY.

GAME ADJUNCT.

1,105,478.

Specification of Letters Patent.

Patented July 28, 1914.

Application filed May 23, 1914. Serial No. 840,581.

To all whom it may concern:

Be it known that I, JOHN W. AMES, a citizen of the United States, residing at East Rutherford, in the county of Bergen and

5 State of New Jersey, have invented new and useful Improvements in Game Adjuncts, of which the following is a specification.

This invention relates to improvements in game apparatus and proposes a device which 10 is adjunctive to the games of pool or billiards and is in the nature of a combination finger brace, cue-rest and guide.

The principal objects of the invention are to provide a device of the character stated 15 which will allow the cue to be efficiently manipulated at different angles for the different kinds of shots contemplated, and in such use while providing an efficient guide will permit of absolute freedom of movement of 20 the cue; which steadies the hand in any position of the cue; which enables the hand regardless of the angle at which the cue is held relatively to the cue ball to rest substantially flat upon the table; and which 25 may be conveniently held in the hand by the player throughout the game and instantly and easily adjusted to any one of several playing positions in accordance with the angle at which the cue is to be held relatively 30 to the cue ball in making the shot.

A further object of the invention is to provide a device for the purposes stated which may be inexpensively manufactured, which is neat and inconspicuous in use, and which 35 is absolutely free of the cue in connection with which it is used. The improved device, having the operative characteristics above stated, promotes skill and *finesse* in the execution of the game referred to, especially in cases where a player finds it difficult to acquire the "knack" of holding his cue and making his stroke.

An embodiment of the invention is illustrated in the accompanying drawings 45 wherein:—

Figure 1 is an elevation of a combination finger brace, cue rest and guide in which the features of the invention are incorporated; Fig. 2 is a plan view thereof; and Figs. 3 50 4 and 5 are perspective views illustrating

different positions of the device for different shots, and different methods of holding the device in the hand in accordance with the position thereof.

Similar characters of reference designate 55 corresponding parts throughout the several views.

The device shown in the drawing is designed to be held by the left hand and assumes that the player, as usual, manipulates 60 the cue with his right hand. For left-handed players, *i. e.*, players who manipulate the cue with their left hands and guide the same with their right hands, a construction the same as that shown in the drawing 65 is used but the parts thereof will be re-arranged in an obvious manner.

The device is preferably of integral construction and may be made of wood or other suitable material. The said device includes 70 what, for convenience, may be termed a base portion 1 which has a flat table-engaging portion 1 which has a flat table-engaging under face 2. The principal position of the device is illustrated in Fig. 3, and in such position the device rests with its flat face 2 75 upon the table. For convenience of description the location of the parts of the device shall be spoken of in relation to the principal position thereof shown in Fig. 3, and with this understanding it will be understood that the base 1 and its flat face 2 80 are horizontally disposed.

The device has a vertical depth of approximately an inch and a half and includes a block 3 upright from the base 1 at one 85 end thereof, specifically at the left end of the base when Figs. 1 and 3 of the drawings are considered, and a block 4 upright from the base at the other end thereof.

The block 3 is in the longitudinal plane 90 of the base but the block 4 is in a plane oblique to the longitudinal plane of the base. To be more exact, the block 4 has a front face 5 which is co-planar with the front faces of the base 1 and the block 3 95 and a rear face 6 which extends at an angle to the rear face of the base 1 and the block 3. The device is formed between the blocks 3 and 4 with a relatively wide finger groove 7 which extends in a slightly diagonal di- 100

rection between the front and rear faces and which has its vertical walls defined by the adjoining confronting faces of the blocks 3 and 4.

5 The block 3 is co-extensive in width with the base 1 and is formed with a finger opening 8 which extends between its front and rear faces and has its wall of uninterrupted annular outline. The opening 8 has a somewhat oblique extent and its axis is approximately parallel to the axis of the recess 7.

The block 4 when viewed from its rear face has a generally rectangular or oblong outline, as shown in Fig. 1, but when viewed 15 in plan has a generally triangular outline, as shown in Fig. 2, and by virtue of the obliquity of its rear face includes a portion, adjoining the groove 7, which projects rearwardly beyond the plane of the rear face of 20 the block 3. The block 4 is formed with a relatively wide groove 9 which has a direction of extent normal to its oblique rear face and, hence, has its axis converging forwardly toward the axis of the groove 7.

25 The diameter of the opening 8 conforms generally to the width of the groove 7 and the said opening 8 and groove 7 are essentially for the reception of the fingers. The groove 9 is a cue groove but in at least one 30 position of the device, (Fig. 5), serves as a finger groove.

The device is completed by a relatively shallow horizontal groove 10 formed in the outer vertical face of the block 3 and serving primarily as a cue groove.

The drawings show, by way of example, three positions of the device, although other useful positions thereof will readily suggest themselves to the skilled player. The principal position of the device is illustrated in Fig. 3 and is the one which is adopted for the majority of shots wherein the cue is held at a relatively slight angle, or in some cases nearly parallel to the plane of the table. In 45 this position, (and which, as above stated, is the one contemplated in the preceding description), the little finger is held adjacent and preferably through a portion of its extent within the groove 10, the third finger 50 is held within the opening 8, the middle finger is held within the groove 7, the fore finger is extended forwardly and slightly bent, and the thumb is held adjacent the oblique rear face of the block 4. The tips 55 of the little finger, the third finger, the middle finger and the thumb rest upon the table and the palm of the hand rests flat upon the table. The cue rests in the groove 9 and is manipulated between the fore finger and the 60 middle finger. The fore finger, which is bent or crooked over the middle finger, is supported upon the rearwardly projecting portion of the block 4, the said rearwardly

projecting portion having its upper surface beveled off as at 11 to easily conform to the 65 cutline of the palm of the hand adjacent the base of the fore finger.

In the positions shown in Figs. 4 and 5, and especially in the latter position, the device may be used in lieu of a bridge. In the 70 position shown in Fig. 4 the device is set on end in an inclined plane and the generally flat oblique face 6 of the block 4 rests upon the table while the cue rests in the groove 10 which, in such position, serves as a support 75 and guide for said cue. In this position of the device the little and third fingers rest upon the table at the left side of the block 4, the middle finger is inserted through the groove 7 and is used to grip the device, the fore finger and thumb rest upon the table at the right of the block 4, and the said block projects against and is steadied and held in position by the pressure of the palm of the hand. Fig. 5 shows a third position of the 80 device wherein it is held perpendicular or substantially perpendicular to the table. In this case the vertical edge of the block 4 at the right end of the device, (Fig. 1 being considered), rests upon the table, the third 85 and little fingers are held upon the table at the left side of the block 4, the middle finger is held in the groove 9, the fore finger is inserted through the opening 8, the thumb is held upon the table at the right side of the 90 block 4 and the cue is manipulated with reference to the groove 10 as a guide but across the front edge of said groove. In the 95 position shown in Figs. 4 and 5 that face of the device which in the position of Fig. 3 100 was termed the "rear" face is presented forwardly and the flat forward face of the device is presented rearwardly and adjacent the palm of the hand.

For the "break" in the game of pool, the 105 device is positioned on the table ledge, as in Fig. 3, but the palm of the hand is held upon the block 3 and the four fingers project forwardly from this block and rest over and upon the inner table ledge while 110 the thumb is inserted through the groove 7. The groove 9 in the block 4 in such case constitutes the only guide for the cue.

Having fully described my invention, I 115 claim:—

1. A device of the character set forth having a base provided with a flat engaging face and two blocks upright from the base and located at opposite ends thereof, one block being arranged in the longitudinal 120 plane of the base and having an opening therein extending between its front and rear faces, the device having a relatively wide and deep groove intermediate said blocks and extending between its front and rear 125 faces on an axis generally parallel to the

axis of the opening, the other block having a relatively wide and deep groove which extends between its front and rear faces and has its axis converging forwardly toward 5 the axis of said first-named groove.

2. A device of the character set forth having a base provided with a flat engaging face and two blocks upright from the base and located at opposite ends thereof, one 10 block being arranged in the longitudinal plane of the base and having an opening therein extending between its front and rear faces, the device having a relatively wide and deep groove intermediate said blocks 15 and extending between its front and rear faces on an axis generally parallel to the axis of the opening, the other block having a relatively wide and deep groove which extends between its front and rear faces and 20 has its axis converging forwardly toward the axis of said first-named groove, said last-named block also having its front face co-planar with the front faces of the base and of said first-named block and having its 25 rear face oblique and converging forwardly and outwardly to its front face.

3. A device of the character set forth having a base provided with a flat engaging face and two blocks upright from the base, and 30 located at opposite ends thereof, one block being arranged in the longitudinal plane of the base and having an opening therein extending between its front and rear faces, the said opening having an uninterrupted 35 annular wall, the device having a relatively wide and deep groove intermediate said blocks and extending between its front and rear faces on an axis generally parallel to the axis of the opening, the other block having a 40 relatively wide and deep groove which extends between its front and rear faces and has its axis converging forwardly toward the axis of said first-named groove.

4. A device of the character set forth having a base provided with a flat engaging face and two blocks upright from the base and located at opposite ends thereof, one 45 block being arranged in the longitudinal plane of the base and having an opening therein between its front and rear faces, and a relatively shallow groove in its outer end face also extending between its front and rear faces, the device having a relatively wide and deep groove intermediate said 50 blocks and extending between its front and rear faces on an axis generally parallel to the axis of the opening, the other block having a relatively wide and deep groove which extends between its front and rear faces 55 and has its axis converging forwardly toward the axis of said first-named relatively wide and deep groove.

5. A device of the character set forth hav-

ing a base provided with a flat engaging face and two blocks upright from the base 65 and located at opposite ends thereof, one block being arranged in the longitudinal plane of the base and having an opening therein between its front and rear faces, and a relatively shallow groove in its outer end 70 face also extending between its front and rear faces, the said opening having an uninterrupted annular wall, the device having a relatively wide and deep groove intermediate 75 said blocks and extending between its front and rear faces on an axis generally parallel to the axis of the opening, the other block having a relatively wide and deep groove which extends between its front and rear faces and has its axis converging forwardly 80 toward the axis of said first-named relatively wide and deep groove.

6. A device of the character set forth having a base provided with a flat engaging face and two blocks upright from the base 85 and located at opposite ends thereof, one block being arranged in the longitudinal plane of the base and having an opening therein between its front and rear faces, and a relatively shallow groove in its outer 90 end face also extending between its front and rear faces, the said opening having an uninterrupted annular wall, the device having a relatively wide and deep groove intermediate 95 said blocks and extending between its front and rear faces on an axis generally parallel to the axis of the opening, the other block having a relatively wide and deep groove which extends between its front and rear faces and has its axis converging forwardly 100 toward the axis of said first-named relatively wide and deep groove, said last-named block also having its front face co-planar with the front faces of the base and of said first-named block and having its 105 rear face oblique and converging forwardly and outwardly to said front face.

7. A device of the character set forth having a base provided with a flat engaging face and two blocks upright from the base 110 and located at opposite ends thereof, one block being arranged in the longitudinal plane of the base and having its outer end face provided with a relatively shallow groove extending between its front and rear 115 faces, the device having a relatively wide and deep groove intermediate said blocks and extending between its front and rear faces, the other block having its front face co-planar with the front faces of the base 120 and of said first-named block and having its rear face oblique and converging forwardly and outwardly to its front face and having also a relatively wide and deep groove extending between its front and rear 125 faces on an axis which converges forwardly

toward the axis of said first-named relatively wide and deep groove.

8. A device of the character set forth having a flat engaging face, an opening adjacent one end thereof extending between its front and rear faces, a relatively shallow groove in its end face nearest said opening and also extending between its front and rear faces and a relatively wide and deep groove adjacent its other end and extending

obliquely between its front and rear faces on an axis which converges forwardly toward the axis of said opening.

In testimony whereof I have hereunto set my hand in presence of two subscribing witnesses.

JOHN W. AMES.
